FIRE ALARM SYSTEM

Charles L. Hill, Cranford, and Lawrence Fahn,
North Plainfield, N. J.

Application July 1, 1939, Serial No. 282,412

5 Claims. (Cl. 200—81)

This invention relates to improvements in fire alarm systems and has particular reference to an electric circuit closer therefor.

The primary object of the invention resides in an electric circuit closer or switch for fire alarm systems in which the increased air pressure caused by heat in pipe-line circuits serves to actuate the same for closing an electric alarm circuit to audibly and/or visually give warning of a fire which may occur on the property protected by the alarm system.

Another feature of the invention is to provide an electric circuit closer which is readily responsive to an unusual rise in temperature on the premises protected by the system in which the circuit closer is arranged, but which is non-responsive to natural atmospheric temperatures so as not to sound false fire alarms.

A still further feature of the invention is the provision of an electric circuit responsive to unusual temperature rises which functions on an overbalancing principle and which includes a novel means of preventing the accidental overbalancing of the circuit closer when the system is installed on ships which may be caused by the tossing of a ship during stormy weather which otherwise would cause a false operation of the circuit closer device.

A still further feature of the invention is to provide a fire alarm system which is simple and inexpensive of construction, easy of installation, and exceptionally sensitive to a sudden rise in temperature upon the property protected by the fire alarm system.

Other features of the invention will be apparent as the following specification is read in conjunction with the accompanying drawing, in which:

Figure 1 is a front elevational view of our improved fire alarm system with parts broken away in section.

Figure 2 is a vertical transverse sectional view approximately on the line 2—2 of Figure 1 including the electrical alarm circuit.

Figure 3 is an enlarged detail vertical sectional view through one of the air relief vents and the air inlet leading thereto.

Referring to the drawing by reference characters, the numeral 10 designates an air pressure electric circuit closer which includes a flat base 11 having an inverted U-shaped frame 12 fixed thereto and rising upwardly therefrom. The frame 12 comprises a pair of spaced vertical parallel rails 13—13 and a top bridge rail 14. Tapped into opposite ends of the bridge rail 14

are ducts 15—15, the inner ends of each of which opens into an enlarged recess 16 which opens onto the top and bottom of the top bridge rail through reduced round holes 17. The outer portion of each duct is screw threaded and threadedly receives a tube 18 forming part of a pipe coupling 19 between the bore 15 and one end of an air pressure detector tube or pipe line 20. The detector tube or pipe line 20 is constructed of flexible material to permit the installation of the same about a room or premises intended to be protected by the fire alarm system and by reference to Figure 1 of the drawing, it will be seen that the pipe line 20 is continuous and the ends thereof are respectively connected to the ducts 15—15 by means of the couplings 19—19. Extending through each pair of vertically aligned holes 17—17 and recess 16 is a bolt 21 having a threaded shank 22 which extends beyond the top of the bridge rail 14, and a head 23, there being a sealing washer 24 interposed between the head 23 and the underside of the bridge rail. A relatively small bore 25 extends axially through the bolt 21 and radial openings 26 establish communication between the bore 25 and the recess 16. A nozzle 27 having an internally screw threaded nipple 28 is threaded to the projecting end of the bolt 21 and a sealing washer 29 is interposed between the nipple 28 and the top surface of the bridge rail 14. The upper end of the nozzle 27 terminates in a tapered portion and fitting into the bore 30 of the nozzle at the tapered end is a relatively small diameter steel rustproof tube 31. An inverted cone shaped housing member 32 is threaded to the nozzle 27 and the upper portion thereof is disposed in spaced relation to the tube 31 and is provided with air outlet holes 33 in the side walls thereof.

From the description thus far, it will be understood that the ends of the detector tube 20 communicate with the atmosphere through air relief nozzles 33, but by means of restricted passages defined by the small diameter tubes 31.

Mounted in horizontally aligned bearing screws 34—34 which are mounted in the vertical rails 13—13 and bridging the space therebetween, is a rod 35. Fixedly mounted on the rod 35 in substantially vertical alignment with the bolts 21—21 are a pair of normally balanced electric switch actuating members 36—36 and in view of the fact that they are identical in construction and attachment to the rod 35, a description of one will suffice for the other.

Each switch actuating member 36 includes a

light weight U-shaped glass tube 37 having a short leg portion 38 opening to the atmosphere through the outwardly flared open end 39, and a long leg portion 40 which terminates in an inwardly offset reduced tapered end 41 normally disposed in vertical alinement with the rod 35 and a bolt 21. The glass tube 37 is connected to the rod 35 by fixed clamping plates 42-42 and the clamping plates are in turn loosely mounted on the rod 35 for turning movement but are held against sliding movement by collars 43 fixed to the rod whereby the U-shaped glass tubes 37 are pivotally mounted on the rod for independent rocking movement relative to each other.

The tapered ends 41 of the two actuating members 36-36 are respectively connected to the bores 25 of the bolts 21 by relatively small diameter flexible tubes 44. The tubes 44 are coiled to provide sufficient slack to enable free swinging movement of the members 36.

Each U-shaped glass tube 37 contains a quantity of liquid substance 45 which is relatively light in weight and of a quality which is relatively slow in evaporation under atmospheric conditions. The liquid substance 45 fills the bight portion of the glass tube and rises in columns into the leg portions 38 and 40 thereof to a level approximately one half the length of the leg portion 38.

Mounted on the base 11 and insulated therefrom is a support in the form of a wall 46, the same rising from the base and being disposed adjacent the leg portions 40 of the glass tubes 37. Insulated from the support 46 are a pair of spring contact members 47-47, the same being respectively disposed in the path of outward swinging movement of the leg portions 40 of the glass tubes 37. The spring contact members 47 are normally disposed in spaced relation to fixed adjustable contact screws 48 threaded in the support 46. The support 46 is of conducting material and the same is connected to a ground 49 forming part of an electric alarm circuit 50 in which the spring contacts 47-47 are arranged in parallel with a battery or other source of electric energy 51, one pole of which is grounded as at 52. Also arranged in the alarm circuit 50 is an audible electric bell 53 and a manually actuated master switch 54. In installation wherein a plurality of individual fire detector pipes 20 and switch actuating devices 36 are arranged, the same may be operatively connected by electric circuits similar to the circuit 50 to an annunciator 55 for visually indicating the particular station detector units as they respond to excessive temperature rises in the confined areas protected by this improved fire alarm system.

In practice, the balanced switch actuating members 36-36 of a detector unit assume the normal position shown in full lines in Figure 2 of the drawing, wherein the same are disposed in spaced relation with respect to the spring contact members 47-47. The pipe or tube 20 contains air and any gradual rise in temperature which may cause expansion of the air therein is exhausted to the atmosphere through the restricted air discharge tubes 31. Should the tube 20 be subjected to a sudden rise of temperature such as would occur by reason of a fire in the vicinity thereof, the expansion of the air within the tube would create an increased air pressure therein which would not be exhausted to the atmosphere through the restricted discharge

tubes 31, and this excess air pressure finds its way to the restricted tubes 44 and into the long legs 40 of one of the switch actuating members 36. Should the fire be closer to one end of the tube than the other, that switch actuating member 36 at that end will function first. The air pressure entering a leg 40 forces the liquid substance 45 therein into the shorter leg 38 causing an overbalancing of this actuating member whereupon the leg 40 forcibly strikes its related spring contact member 47 and forces it into contacting engagement with its related contact screw 48, thereupon closing the circuit 50 and setting off the audible alarm device 53 and indicating the set off station detector unit on the annunciator 55. The circuit closing position of the actuating member 36 is illustrated in dotted lines in Figure 2 of the drawing. In use, the switch actuating unit 10 may be enclosed in a casing to prevent the accumulation of dust and dirt thereon and also prevent undue evaporation of the liquid substance 45. Should the liquid substance 45 drop below a predetermined level, the same may be replaced by a fresh supply poured into the leg portion 38 through the open flared end 39.

When the fire alarm system is installed on ships, it is possible that the roll of a ship may cause a false alarm due to the tilting of the actuating members 36 in the direction of the spring contacts 47. To prevent such an occurrence, we have provided an automatic stop for arresting accidental movement of the members 36. Pivoted at 56 to the inner side of one of the side rails 13 is an inverted L-shaped counter balance lever 57 which carries a balance weight 58 at its lower end. The short leg 59 of the inverted L-shaped lever 57 is provided with a stop arm 60 which extends through the U-shaped glass tubes 37 and is normally disposed adjacent the short legs 38 but clear of the limit of the normal actuating movement so as not to interfere with the movement of the actuating members to circuit closing position when the unit 10 is in a vertical position. However, should the unit be tilted in a direction which would cause the spring contacts 47 to move toward the legs 40 of the members 36, such movement will be prevented by the arm 60 which is disposed in the path of movement of the legs 38 by reason of the counterbalance weight 58.

While we have shown and described what we consider to be the preferred embodiment of our invention, we wish it to be understood that such changes in construction and design as come within the scope of the appended claims may be resorted to if desired.

Having thus described the invention, what we claim as new and desire to secure by Letters Patent of the United States, is:

1. A circuit closer device comprising a support, a horizontal rod fixedly mounted in said support, a holder member rockably mounted on said shaft, a substantially U-shaped tube member having leg portions and a bight portion, means connecting the leg portions to said holder equidistant from the axis of turning movement of said holder member, an inwardly offset tubular extension formed integral with one leg portion of said U-shaped tube member, said tubular extension terminating in a restricted air pressure inlet, a length of relatively small diameter flexible tubing having one of its ends fitted into the inlet while the other end of said tubing is adapted to be connected to an air pressure line, and a liquid substance partially filling said U-shaped

tube member and serving to assist in normally holding the same in balance whereby air pressure in excess of atmospheric pressure which may be introduced into said tube member through the inlet end thereof will cause the shifting of the liquid substance from the inlet leg portion to the other leg portion of the U-shaped tube member to effect an overbalancing of the tube member to cause the lower portion of the inlet leg portion to swing outwardly in an operating direction, and an electric push switch arranged in the path of outward operative swinging movement of the said inlet leg portion for actuating the same.

2. A circuit closer device comprising in combination a base, a pair of spaced opposed rigid uprights rising upwardly from said base, a rod having its ends respectively mounted in said uprights, a cross arm rockably mounted on said rod, a substantially U-shaped tube member having spaced leg portions and a connecting bight portion, means connecting the leg portions to said cross arm equidistantly from the axis of said rod, a restricted air inlet provided in the free end of one leg portion while the free end of the other leg portion opens to the atmosphere, a liquid substance partially filling the U-shaped tube member and extending into the leg portions thereof to assist in normally holding the U-shaped tube member in suspended balance whereby air pressure in excess of atmospheric air pressure when introduced into the U-shaped tube member through the inlet end thereof will cause the shifting of the liquid substance from that leg portion having the air inlet to the other leg portion to effect an overbalancing of the U-shaped tube member to cause the lower portion of the leg portion having the air inlet to swing outwardly in an operating direction, a bracket mounted on said base, a fixed electric contact mounted on said bracket, and a spring contact mounted on said bracket and normally out of engagement with the fixed contact, said spring contact being disposed in the path of outward operative swinging movement of the U-shaped tube member to be strikingly engaged thereby for movement into engagement with said fixed contact.

3. A circuit closer device as set forth in claim 2, including a pendulum member pivotally mounted on one of the uprights, and a stop arm on said pendulum member disposed in the path of the U-shaped tube member for arresting accidental swinging movement of the same in an operating direction when the device is accidentally tilted in such direction.

4. A circuit closing device comprising a sup-

- port, a substantially U-shaped tube member pivotally mounted intermediate its top and bottom in pendulum fashion on said support for swinging movement, said U-shaped member having a short leg portion having its end opening to the atmosphere, a long leg portion having an air pressure inlet at its end, and a bight portion connecting the leg portions; a liquid substance contained within said tube member and rising into the legs at a common level, a normally open electric push spring switch mounted on said support to one side of the U-shaped tube member and disposed in the path of outward swinging movement of the long leg portion whereby air pressure in excess of atmospheric air pressure which may enter the long leg portion through the pressure inlet will cause the level of the liquid substance in the short leg portion to rise and that in the long leg portion to drop to effect an overbalancing of the tube member to cause the long leg portion thereof to strikingly engage the push switch, and a counterbalance stop member mounted on the support and disposed in the path of switch closing swinging movement of the tube member to prevent accidental actuation of the push switch upon accidental tilting of the support.
5. A circuit closer device comprising a support, a substantially U-shaped tube member having an air pressure inlet at one end, the other end of said member opening to the atmosphere, means for pivotally mounting said tube member intermediate its top and bottom in pendulum fashion upon said support, a liquid substance contained in said tube member and only partially filling the same, said tube member being normally in a balanced perpendicular position, whereby air in excess of atmospheric air which may be introduced into said tube member through the inlet end thereof will effect a shifting of the liquid substance from one side of the pivotal axis of the U-shaped tube member to the other side thereof to effect an overbalance of said tube member to cause the lower end thereof to swing outwardly in an operating direction, a push switch element disposed in the path of outward swinging operating movement of said tube member for actuation thereby, and a stop means in the path of outward swinging operating movement of the U-shaped tube member for arresting the swinging movement of the tube member in an operating direction when the support is tilted to prevent accidental actuation of the push switch element.
